UNITED STATES PATENT OFFICE

2,644,073

DIELECTRIC HEATING WITH ROTATORY WORK-RECEIVING ELEMENT

Paul D. Newhouse, Salix, Iowa, assignor to Westinghouse Electric Corporation, East Pittsburgh, Pa., a corporation of Pennsylvania

Application April 1, 1949, Serial No. 84,881

3 Claims. (Cl. 219—47)

1

Broadly, my invention relates to means for the dielectric heating of dielectric material, with apparatus utilizing a rotatory element that carries the material inside of it. More particularly, my invention relates to means for the dielectric heating of non-gaseous fluidic materials that have characteristics of flow. For want of better terminology, the term "non-gaseous fluidic material," is intended to embrace liquids and divided, granular, or powdered particles.

In accordance with preferred forms of my invention, the work or material is carried inside a rotatory element through a radial high-frequency field produced by stationary electrodes that have no physical contact with the rotatory element. Such a structure has the advantage of eliminating the need for sliding or rolling contacts, brushes etc., which cause arcing and energy losses, and are otherwise troublesome.

A general object of my invention is to provide a means of a type described for the dielectric heating, for any purpose, of non-gaseous fluidic material; and a particular object in this connection is to accomplish such heating on a continuous mass-production basis.

A further object of my invention is to provide a dielectric heating system of a type described in which a radially-extending electric field is provided at the inner surface of a rotating tubular member or container by means of an inner electrode on the inside of the tubular member or container, the electrode being insulated therefrom.

Another object of my invention is to provide a dielectric heating system of a type described in which the radial field is established by a stationary electrode inside a work-receiving container, and another stationary electrode outside of the container. The container has a wall which holds the work to be heated, and all or a portion of this wall moves between the two stationary electrodes as it rotates. The container is of metal, and is capacitively coupled to the outer electrode for feeding electrical energy into the work. By making the outer electrode a tube which completely surrounds the container and by grounding this outer electrode, a high degree of safety for operators of the apparatus is obtained.

Objects, features and innovations of my invention, in addition to the foregoing, will be discernible from the following description of several preferred forms thereof. This description is to be taken in conjunction with the accompanying drawings in which details not essential to an

understanding of the invention have been omitted in the interests of simplicity and clarity. In the simplified drawings, which are not to scale, Figure 1 is a vertical axial sectional view of an embodiment of my invention;

Figs. 2 and 3 are sectional views along the lines II—II and III—III, respectively, of Fig. 1;

Fig. 4 is a vertical sectional view, corresponding to Fig. 2, of another embodiment of my invention;

Fig. 5 is a vertical sectional view of a further embodiment of my invention;

Fig. 6 is a horizontal sectional view on the line VI—VI of Fig. 5; and

Figs. 7 and 8 are partial vertical sections of further modifications of my invention.

The broader aspects of my invention can find expression in many different embodiments, each constituting a new and useful improvement in its own right. In this application, my invention is shown in several forms. One comprises a rotary kiln comprising a tubular member through which discrete solid particles are passed for dielectric heat-treatment. A further form is in the nature of a drying centrifuge. Still another form of my invention which utilizes rollers between which sheet material moves, is described and claimed in my copending application Serial No. 84,882, filed concurrently herewith:

Figs. 1 through 4 show my invention embodied in a rotary kiln-type apparatus. Work or material 2 in the form of discrete particles such as, by way of example only, grain particles, is slowly fed from a hopper 4 to the upper open end of a rotatory work-receiving member or tumbler having a wall in the form of a tube or tubular member 6 of metal. The other end of tumbler tubular member 6 has an insulating plate 8 secured therein that is provided with a plurality of circumferentially spaced openings 10 around its outer periphery. The tumbler tubular member 6 is rotatably supported at its lower end. This supporting means comprises a shaft 12 secured to the center of the insulating plate 8 and a bearing or bearings 14 for the shaft. The shaft 12 is rotated by any suitable driving means. The tumbler tubular member 6 constitutes a work-receiving container and has a helical work-guide 16, of exceptionally low-loss insulation, secured to its inner surface for assuring downward movement of particles of material 2 fed to the member 6 from the hopper 4. Similarly, spaced insulating longitudinal tumbling strips 17 can be secured to the inside of the tumbler, between the turns of the work-guide 16. Material passing

through the tubular member 6 discharges therefrom through openings 10 and falls into any suitable work-receiving means 12.

A high-frequency electric field is established through the work-carrying portion along the lower side of the tumbler tubular member 6, through means comprising an inner electrode 22 and an outer electrode 24. The inner electrode 22 comprises a curved metal plate 26 carried by an insulating support 28 that includes a rod 29 that passes through the upper open end of the tumbler tubular member 6. This rod may be fastened to any suitable structure that holds the support 28 and the electrode 22 stationary inside the tumbler tubular member 6, so that the curved plate 26 of the electrode 22 is spaced from the tumbler tubular member 6. By stationary, I do not mean absolutely fixed with respect to the ground, since I contemplate adjustably positioning the plate 26 inside the tumbler tubular member 6 at different distances from the tumbler tubular member 6, and either substantially concentric or coaxial therewith or with its axis at an angle therewith.

The outer electrode 24 also comprises a curved metal member in the form of a stationary metal tube 30 that completely encompasses the tumbler tubular member 6. This tube 30 is also concentric with the tubular member 6. The nested members, comprising the inner plate 26, the outer tube 30 and the intermediate tubular member 6 are electrically insulated from each other, and arranged to give any suitable spacing between them.

The upper part of the inner electrode 22 can be provided with a pair of insulating boards 32 and 34 of proper length to form a tent or dihedral angle over the hollow portion of the curved plate 26 so as to prevent any particles that ride too far up the tubular member 6 from falling into the hollow portion of the curved plate 26 of the electrode 22.

High-frequency energy is supplied to the electrodes 22 and 24 by any suitable means. For example, it may be applied by means of a transmission line comprising a coaxial cable having an outer grounded conductor 36 and an inner insulated conductor 38. The insulated conductor 38 is directly electrically connected to the insulated metal plate 26 of the inner electrode 22. The grounded conductor 36 is electrically connected to the tube 30 of the outer electrode 24, either directly or through ground, the tube being shown grounded at 40. A tube-oscillation generator (not shown) can be connected, through any suitable control apparatus, to the coaxial cable as a source for the high-frequency energy, which for dielectric heating usually has a frequency in the order of megacycles. The outer electrode 24 is capacitively coupled to the tumbler tubular member 6 through the air space between them.

When the electrodes 22 and 24 are energized, a high-frequency voltage exists across them and an electric field is provided that passes radially through that lower portion of the tumbler tubular member 6 which happens to be between the facing parts of the plate 26 and tube 30 of the electrodes. The radial electric field thus provided dielectrically heat-treats the particles of material 2 as they move downwardly during the rotation of the tumbler tubular member 6.

An important feature of my invention resides in the fact that no direct electrical connection is required between the tumbler tubular member

6 and either of the electrodes 22 and 24 in order to establish a radial field inside of the tubular member, that passes through the lower work-carrying portion thereof. Also, by grounding the tube 30 of the outer electrode 24 and by having it substantially completely encompass the tumbler tubular member 6, the high-potential parts of the dielectric heating apparatus described are well screened, and a high degree of safety is assured for operators around the apparatus.

Fig. 4 represents a modified form of apparatus which corresponds substantially to that described in connection with Figs. 1 through 3, except that the inner electrode is made in the form of a complete metal tube 42 instead of a partly cylindrical metal plate, such as plate 26. Such construction will provide a complete radial electric field around the full inside surface of the tumbler tubular member 6.

Fig. 5 shows a drying centrifuge embodying the principles of my invention. Referring to this figure, the rotatory work-receiving tubular member 50 comprises a pair of nested or concentric tubular elements or walls 52 and 54 that are spaced to provide a work-receiving space in which a non-gaseous fluidic work or material 56, such as, for example, silica gel to be dried, or cloth material to be dried, is received. An annular bottom 58 of insulation closes the space between the inner tubular element 52 and the outer tubular element 54. The rotatory tubular member 50 is carried on an insulating disc 60 which is rotatably carried on a hollow shaft 62 journalled in a bearing or bearings 64. When the hollow shaft 62 is rotated, it is evident that the tubular member 50 will also rotate at a speed depending on the rotational speed of the shaft 62. The shaft can be driven at any desired speed by any suitable means.

For providing a radial electric field through the annular-like work-receiving space of the tubular member 50, a pair of curved electrodes 66 and 68 are provided; the former being inside the tubular member 50 and the latter outside of it. The inner and outer curved electrodes 66 and 68 respectively can be supported in any suitable manner so as to be concentric with—but stationary with respect to—the rotatory tubular member 50.

The supporting means shown for the inner electrode 66 comprises a stationary shaft 70 that passes upwardly through the hollow rotatable shaft 62. The shaft 70 extends upwardly beyond the insulating disc 60 and carries cross-bars 72 which, in turn, carry the inner electrode 66 which is in the form of a metal tube 74 but obviously can be of some other shape. The outer electrode 68 is in the form of a metal tube 76 that is carried on a frame 80. For supplying high-frequency voltage across the electrodes 66 and 68, a transmission line is connected to the electrodes, with its insulated conductor 82 detachably secured to the inner tube 74 of the inner electrode 66, and its grounded conductor 84 electrically connected to the tube 76 of the outer electrode 68 through a suitable connection, shown as a ground connection 86.

The rotatory tubular member 50 constitutes a work-receiving container or cage which is the only rotating part of the apparatus except for the driving shaft and the supporting means from the shaft to the tubular member. The high-voltage electrode 66 on the inside of the container is practically entirely surrounded by material

5

being processed and by the grounded outer electrode 68.

The tubular elements or walls 52 and 54 of the tubular member 50 can be constructed in any desired manner suited to the purpose to which my invention is applied, which may be drying, centrifugal separation, or any other purpose for which centrifuges or rotatory tubular members are commonly used. An apparatus of the type shown is especially suited for treating viscous materials, such as, for example, oil from which water is to be removed, etc. The viscosity of highly viscous materials is reduced with heat, and vapors are driven off which can be removed by an air blast 88 which blows air upwardly through the space between the outer tube 76 and the outer tubular element 54 of the rotatory tubular member 50. To permit this use of the apparatus, the inner tubular element 52 can be made from sheet metal, and the outer tubular element 54 can be made from a metal screen or perforated sheet metal that allows easy passage of liquid or vapor. If desired, the outer tubular member 76 of the outer electrode 68 can also be made from metal screening or the equivalent. Copper or aluminum is recommended for the metal parts of the apparatus, unless either reacts with the material being processed. In such case, any other suitable low conductivity metal or plated metal can be used. Obviously, for heating liquids the two tubular elements 52 and 54 of the tubular member or container 50 should be solid.

In order to permit the container to be easily loaded and unloaded, the insulation disc 60 that supports the tubular member 50 can be provided with an annular seat 90 in which the tubular member removably sits so that the member can be lifted out of the apparatus whenever desired, and then restored.

For best electrical efficiency, the voltage across the space or spaces between the stationary and rotating parts should be as low as possible so that most of the voltage supplied by the generator appears across the material being heated. Figs. 7 and 8 show improved means for raising the proportion of voltage across the useful load with respect to the voltage required for the capacitive coupling.

In Fig. 7, the rotating insulating disc 100 carries a work-holding tubular member 102 comprising a metal outer tube 104 and a metal inner tube 106. The stationary parts comprise an outer set of concentric metal tubes 108 and 110, which are grounded, and an inner set of concentric metal tubes 112, 114 and 116 which are connected to an insulated high-voltage high-frequency conductor 118.

Unitary with and electrically connected to the outer tube 104 of the work-holding member 102 is a metal tube 122. The tube 122 is concentric with the tubes 108 and 110 and rotates between them. Similarly, the inner tube 106 of the work-

6

holding member 102 is provided with nested metal tubes 124 and 126 to which it is electrically connected. The tubes 124 and 126 rotate between the tubes 112, 114 and 116.

5 In cases where it is not necessary to remove the work-holding container from the disc, the capacitive coupling for providing a voltage across the inner and outer tubes of the rotating container can be arranged as shown in Fig. 8. In 10 Fig. 8, the stationary electrodes 130 and 132 are provided with annular plates 134 and 136 which interleave similar plates 138 and 140 on a rotating work-holding container 142.

15 While I have described my invention in forms which are now preferred, it is obvious that its principles can be applied in other forms and modifications.

I claim as my invention:

1. Dielectric heating means of a type described 20 comprising, in combination, a pair of spaced, upstanding substantially-coaxial, stationary, relatively-insulated, metallic curved electrode-members, an annular-like container substantially coaxial with said electrode-members comprising a plurality of wall members, said container being positioned between said electrode-members, support means for rotatably supporting said container between said electrode-members and insulated therefrom, and means for applying a 25 high-frequency voltage across said electrode-members.

2. An invention including that of claim 1, but further characterized by said container comprising a pair of nested upstanding walls, adapted to 30 contain a non-gaseous fluidic material, that pass between said electrode-members as the container is rotated.

3. An invention including that of claim 1, but further characterized by said container being removable from between said electrode-members.

PAUL D. NEWHOUSE.
